(57) **CLAIM**

The ornamental design for a cocktail shaker, as shown and described.

DESCRIPTION

FIG. 1 is a top, front perspective view of a cocktail shaker; FIG. 2 is a front view thereof, the right side view, left side view, and rear view being a mirror image;

FIG. 3 is a top view thereof;

FIG. 4 is a bottom view thereof;

FIG. 5 is an exploded top, front perspective view thereof; and,

FIG. 6 is a cross-sectional view taken along line 6 of FIG. 2.

All broken lines represent unclaimed features of the article to which the design is applied.
